UNITED STATES PATENT OFFICE.

WARREN W. AMES, OF DE RUYTER, NEW YORK.

ADDRESSING-MACHINE.

SPECIFICATION forming part of Letters Patent No. 235,485, dated December 14, 1880.

Application filed September 27, 1880. (No model.)

To all whom it may concern:

Be it known that I, WARREN W. AMES, of De Ruyter, in the county of Madison and State of New York, have invented certain new and useful Improvements in Addressing-Machines; and I do hereby declare that the following is a full, clear, and exact description thereof, which will enable others skilled in the art to which it appertains to make and use the same, reference being had to the accompanying drawings, which form a part of this specification, and in which—

Figure 1 is a perspective view, and Fig. 2 is a longitudinal vertical section.

Similar letters of reference indicate corresponding parts in all the figures.

My invention relates to machines for addressing newspapers and other mail matter; and it consists in the combination, with the sliding galley and stamp, of a pivoted pawl which feeds the galley forward when the stamp is raised to imprint the address, and a thumb-screw for gaging or regulating the movement of the stamp-lever to suit the type used in making up the galley-form and the number of lines in the address, substantially as herein-after more fully set forth.

In the annexed drawings, A is the base-plate, and B the galley containing the type of each address, set up consecutively, as shown at a. C C are the side pieces, which are extended to form guide-flanges c c, connected on one side by the top plate, D, the upper end or top of the sides C being connected by a cross-bar, E, made with an upwardly-curved lip, e, through which is inserted the thumb-screw F.

G is the stamp-lever, which is pivoted on a pin, g, between the sides C C, and is provided with the stamp or platen H. On one side of

the lever-head is hinged the pawl I, the lower end of which engages with the galley-slide by dropping between the series of type or addresses, so that by raising lever G the galley is moved forward the space of one address.

The throw of the lever is regulated by the thumb-screw F, so as to always bring the type directly below or in a line with the stamp H, which strikes the matter interposed between it and the galley through an open space, h, between the top plate, D, and another plate or cross-piece, D', connecting the sides C C.

From the foregoing description, taken in connection with the drawings, the operation of my invention will be readily understood without further explanation.

The galleys with the addresses to be printed on the mail matter are fed consecutively to the stamp at one end of the box formed by the base A and sides C C, the pawl I working them forward at each rising of the stamp.

Having thus described my invention, I claim and desire to secure by Letters Patent of the United States—

In combination, the frame or casing composed of the base-plate A, sides C C, and upper cross-bar, E, having curved lip or projection e, set-screw F, inserted through said lip, lever G, pivoted between the sides C C, below the set-screw, and provided with the platen H, and pawl I, hung in the shaft of lever G, as shown and specified.

In testimony that I claim the foregoing as my own I have hereto affixed my signature in presence of two witnesses.

WARREN WHITFORD AMES.
